Patented Jan. 2, 1973

225,785

MEDICATION TRAY

David B. Geddis, Somerville, N.J., assignor to
Johnson & Johnson

Filed Aug. 19, 1971, Ser. No. 173,344

Term of patent 14 years

Int. Cl. D24—02, 99

U.S. Cl. D83—1

T1□.1.

T1□.2.

FIG. 1 is a perspective view of the opposite side of the medication tray;

FIG. 2 is a perspective view of the opposite side of the medication tray;

FIG. 3 is a top plan view thereof;

FIG. 4 is a bottom plan view thereof;

FIG. 5 is a side view of the side shown in FIG. 1; and

FIG. 6 is an end view of FIG. 1.

I claim:

The ornamental design for a medication tray, as shown and described.
